UNITED STATES PATENT OFFICE.

GEORGE P. HERNDON, OF BIRMINGHAM, ALABAMA.

AUTOMATIC CUT-OFF FOR WATER-PIPES.

SPECIFICATION forming part of Letters Patent No. 392,803, dated November 13, 1888.

Application filed September 6, 1887. Serial No. 248,958. (No model.)

To all whom it may concern:

Be it known that I, GEORGE P. HERNDON, a citizen of the United States, residing at Birmingham, in the county of Jefferson and State of Alabama, have invented new and useful Improvements in Automatic Cut-Offs for Water-Mains, of which the following is a specification.

This invention relates to certain new and useful improvements in devices for operating the valves of water-pipes, and relates more particularly to that class in which are employed a weighted lever connected with the stem of the valve, a thermo-dynamic column, and connections between said column and valve-stem, whereby an automatic cut-off is provided and the freezing of the water in the pipes prevented by emptying the service-pipe and its branches whenever the temperature shall reach a given point approximating the freezing-point.

20 The object of the present invention is to simplify and cheapen devices of this class and to lessen the number of parts, thereby rendering the device more certain in its action and reducing to a minimum inefficiency from non-working of the parts.

25 The novelty resides in the peculiarities of construction and the new combinations and arrangement of parts, all as more fully herein-after described, shown in the drawings, and 30 then particularly pointed out in the appended claims.

In the drawings which, with the letters of reference marked thereon, form a part of this specification, Figure 1 is an elevation, partly 35 in section, showing my invention; and Fig. 2 is a detail perspective of a portion of the service-pipe shown in Fig. 1, with the automatic cut-off and draw-off attached.

40 Referring now to the details of the drawings, the numeral 1 designates a portion of the service-pipe of a dwelling or building of any suitable description. Interposed in this pipe, at any suitable point, is a valve-box, 2, containing any preferred form of valve or cut-off, that 45 shown being a three-way valve, 3, having a water-way, 4. Cut diametrically in the valve and at right angles to the water-way is a passage, 5, entering the valve-way 4, a spout, 6, being tapped into the valve-box upon the side 50 opposite the passage 5. A valve-stem, 7, pro-

jects through the wall of the valve-box and receives the end of an actuating-lever, 8, which is weighted in any suitable manner—as, for example, by broadening the lever toward its outer extremity. The end of the lever is provided with a detent, 9.

Upon any suitable support, 10, in proximity to the pipe 1, is mounted a bracket, 11, upon which stands a thermo-dynamic column, 12, of any suitable construction and material, the 60 form preferred being a closed brass tube, which gives strength and lightness as well as economy of material, yet is very efficient for the purpose. Directly to the upper end or extremity of this column is pivotally connected the short 65 arm or power end of the lever 13, having its fulcrum 14 upon the support 10, and provided at the other end with an eye, 15, which engages the detent 9 on the lever 8, the length of the lever being such that when the engagement is 70 made the valve-lever 8 will stand at an angle with the perpendicular, as shown in Fig. 1, and be sustained in that position by the eye 15 on the lever 13.

Upon a fall of temperature the column 12 75 contracts, raising the eye 15 upon the end of the lever 13, and when the contraction is sufficient releases the valve-lever. The weight upon the latter causes it to fall, thereby closing the valve 3 and bringing the passage 5 into communication with the service-pipe and with the spout 6. The water contained in the pipe above the valve will run off through this passage and spout, quickly emptying the pipe and its branches.

80 A series of openings, 14^a, are formed in the lever 13, to engage with the removable fulcrum-pin 14 and enable the user to vary the acting distance of said lever, thereby adjusting the device to operate and release the valve-lever 90 8 at any given temperature.

85 The device is simple and inexpensive, certain in action, and not at all liable to get out of order or to deteriorate in use.

Importance is attached to the peculiar arrangement of parts whereby a more positive action is provided, dispensing with the sleeve and other accessories heretofore necessary, and bringing the lever 13 in direct engagement with the lever 8, whereby the contraction of the col- 95 100

umn 12 cannot fail to release the lever 13 from engagement with the lever 8 and operate the valve.

What I claim as new is—

5 1. The combination, with a service-pipe and a thermo-dynamic column, of a lever, 13, connected at one end directly to the upper end of said column, a valve in said pipe, and a weighted lever mounted at one end on the stem of said valve and its other end extended to and engaging the long arm of the lever 13, substantially as and for the purpose specified.

10 2. The combination, with the service-pipe and a three-way valve therein, of the thermo-dynamic column, the pivoted lever 13, having its short arm pivotally connected directly to said column, the eye 15 at the end of the long arm of said lever, and the lever 8, mounted at one end on the stem of said valve and formed 15 at its other end with a detent, 9, engaging di-

rectly with said eye, substantially as shown and described, and for the purpose specified.

15 3. The combination, with the service-pipe and the valve therein, of the support 10, the metallic column parallel with the service-pipe, 20 the weighted lever 8 on the stem of the valve and formed at its other end with detent 9, the lever 13, attached to the upper end of the said column and provided with a plurality of holes, 14, the removable pivot-pin 14, and the eye 25 15 on the outer end of the lever 13 and engaging directly the detent on the lever 8, substantially as shown and described, and for the purpose specified.

In testimony whereof I affix my signature in presence of two witnesses.

GEO. P. HIERNDON.
